UNITED STATES PATENT OFFICE.

JULIUS PRELEUTHNER, OF ERIE, PENNSYLVANIA.

HYDRAULIC PRESS.

1,054,868.

Specification of Letters Patent.

Patented Mar. 4, 1913.

Application filed April 20, 1912. Serial No. 692,186.

To all whom it may concern:

Be it known that I, JULIUS PRELEUTHNER, a citizen of Austria-Hungary, residing at Erie, in the county of Erie and State of Pennsylvania, have invented certain new and useful Improvements in Hydraulic Presses; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam-hydraulic forging presses and has for its object the construction and arrangement of a plurality of steam intensifiers for such a press in such a manner that each may be operated singly, or any two or more intensifiers may be operated simultaneously, whereby a greater range of pressure may be utilized than with presses as ordinarily constructed.

20 In steam-hydraulic forging presses as heretofore constructed, provided with a plurality of intensifiers, it is impossible to operate two or more of such intensifiers in unison, because of the fact that the high-pressure intensifier will overcome the power of 25 the low-pressure intensifier. I overcome these disadvantages by arranging a series of intensifiers of different diameters, each of said intensifiers being provided with a piston and all of said pistons being secured upon 30 a piston-rod in tandem, which piston-rod extends into the fluid chamber of the press and forms the plunger therefor. I arrange the intensifiers preferably super-imposed above the fluid-cylinder of the press and in tandem 35 therewith, but they may, however, be connected with the press in any position desired, as for instance, at one side of the press, upon a suitable foundation of their own, either in vertical or horizontal position and 40 the fluid chamber thereof connected with the fluid-cylinder of the press by any suitable connection. The advantage of this construction is, that each intensifier may be used singly, or any two or more may be used 45 simultaneously, thereby obtaining the combined power of all the intensifiers operated.

50 Another advantage of this construction is, that when the low-pressure intensifier is used only, less steam is required than when 55 the high-pressure is used, which is not the

case with the presses as ordinarily constructed.

The features of my invention are herein-after set forth and explained and illustrated in the accompanying drawings, in which the figure is a view partly in elevation and partly in vertical section of a hydraulic-press embodying my invention.

60 In this drawing A, indicates the base of the press upon which is placed the anvil B, upon which base the upper part of the press is supported by means of columns C. Upon these columns C, is placed the press-frame D, which is adjusted and secured thereon by means of nuts e. Within this frame D, is secured a hydraulic-cylinder E, having in the upper end thereof the usual stuffing-box mechanism E', and also an opening in which is secured a supply-pipe F. Within the cylinder E is placed the press-ram G, having in the upper end thereof a cylindrical recess G'. On the lower end of this ram G, are transverse arms G², the ends of which embrace and slide upon the columns C, and secured beneath the lower end of the ram G, is a die H, which operates in opposition to the anvil B.

65 Super-imposed upon the press-frame D, I place a series of two or more steam intensifiers, consisting of steam cylinders J, J', and J², provided with suitable cylinder-heads j, j', j², j¹ and j². Within each of the cylinders there are pistons K, K', and K², which are mounted and secured in tandem on the piston-rod L, which extends through 70 suitably packed openings in the several cylinder-heads and through the stuffing-box mechanism E', into the hydraulic-cylinder E. For raising the ram G, and die H, I provide steam-cylinders M, in which there 75 are pistons M', from which piston-rods M², extend downwardly through suitable stuffing-box mechanisms m, to the transverse arms G², where they are secured by means of nuts m'. 80

85 The supply-pipe F, is provided with a check-valve mechanism O, of usual and ordinary construction and having a valve-stem O', by means of which the check-valve may be opened to permit liquid to escape from the hydraulic cylinder E, through the pipe F, when it is desired to raise the ram G.

90 The steam cylinder J, is provided with an air-vent, 1, and a steam port opening, 2; the steam cylinder J', is also provided with 95

100

105

110

an air-vent opening, 3, and a steam port opening, 4, and the steam cylinder J^2 is likewise provided with an air-vent opening, 5, and a steam port opening, 6; the cylinders 5 M, are each provided with an air-vent opening, 7, in the upper part thereof, and a steam port opening in the lower part thereof. The steam port openings, 2, 4, 6, and 10 8, are connected with the steam line by means of suitable valves and piping, which, being no part of my invention are not shown and described.

In operation, the ram G, is lowered by exhausting steam from the lower ends of 15 the cylinders M, and water is admitted through the pipe and check-valve F, and O, into the hydraulic-cylinder E, to compensate for the lowering of the ram G, in said cylinder. Steam is then admitted into one or 20 more of the intensifier cylinders J, J', or J^2 , according to the amount of pressure desired, which forces the piston-rod L, downward into the fluid in the hydraulic cylinder E, which, in turn forces the ram G, downward 25 in proportion as the fluid is displaced by the piston-rod L. It will thus be observed that each of the intensifier cylinders operates the same plunger, so that the high-pressure cylinder J, when operated, does 30 not displace any less of the liquid in the cylinder E, than does the cylinder J' or J^2 .

With my arrangement of intensifiers, it is possible to combine any two or more thereof in simultaneous operation, obtaining 35 thereby with three steam intensifiers, seven combinations of pressure, which is a marked advantage as compared with the arrangement of intensifiers heretofore used in connection with hydraulic presses.

40 Having thus shown and described my invention, so as to enable others to construct and utilize the same, what I claim as new and desire to secure by Letters Patent is:—

1. The combination in a hydraulic-press, 45 of a fluid cylinder having an opening in the upper end thereof, a ram mounted in said

cylinder, and extending downwardly therefrom, a cross-head on said ram, a series of steam cylinders removably secured together in tandem, and removably secured concentrically above said fluid cylinder, brackets on the sides of one of said cylinders, a common plunger-rod passing through said series of cylinders and extending into said fluid cylinder, pistons in each cylinder of said series removably secured on said plunger-rod, steam cylinders supported on said brackets, pistons in said cylinders, piston-rods secured in said pistons and extending downwardly therefrom and secured to said cross-head, substantially as set forth.

2. The combination in a hydraulic-press, of a base, an anvil thereon, columns secured in said base, a frame supported on said columns, a fluid cylinder having an opening in the upper end thereof mounted in said frame, a ram mounted in said fluid cylinder and extending downwardly therefrom, a cross-head on said ram, sleeves on said cross-head embracing said column, a series of steam cylinders removably secured together in tandem by means of cylinder heads closing their upper ends, removably secured upon said frame concentrically with said fluid cylinder, brackets on the sides of one of said steam cylinders, a common plunger-rod extending through the series of steam cylinders and downwardly into said fluid cylinder, pistons in each cylinder of said series removably secured on said common plunger-rod, steam cylinders supported on said brackets, pistons therein and piston-rods secured in said pistons extending downwardly therefrom and secured to said cross-head, substantially as set forth.

In testimony whereof I affix my signature, in presence of two witnesses.

JULIUS PRELEUTHNER.
